UNITED STATES PATENT OFFICE.

THOMAS B. BENNETT, OF MUSKEGON, MICHIGAN.

OIL-PUMP NOZZLE.

Application filed November 29, 1926. Serial No. 151,297.

This invention relates to a nozzle for liquid dispensing pumps. Pumps used for dispensing liquid, particularly oil, usually have a considerable dripping of the liquid from the nozzle outlet after the dispensing operation has been completed. Means have been used to eliminate any bad results from such dripping though heretofore, so far as I know, no means has been used to completely remedy the defect and eliminate it. Drain pipes for carrying the drip back to the receptacle from which the liquid has been pumped have been most commonly used.

The present invention is concerned with a simple, practical and economical construction of nozzle in which dripping of oil or other liquid dispensed is completely eliminated so that there is no waste of oil nor any undesirable and messy condition created through the waste oil spreading over the top of the receptacle from which it is pumped.

The invention consists of a novel construction of dispensing nozzle by means of which this result is completely attained in a very effective and satisfactory manner as will be fully understood from the following description, taken in connection with the accompanying drawing, in which,

Fig. 1 is a side elevation of a dispensing pump equipped with the nozzle of my invention.

Fig. 2 is an enlarged front elevation of the nozzle, some parts being broken away and in section to better illustrate the construction.

Fig. 3 is an enlarged vertical longitudinal section through the nozzle.

Fig. 4 is a plan view, somewhat reduced in size, of the trip bar which is operated to open the nozzle to permit the dispensing of liquid.

Fig. 5 is a vertical section through the outlet end of a modified type of nozzle.

Like reference characters refer to like parts in the different figures of the drawing.

The pump may be of any usual and conventional construction and, as shown, includes a cylinder 1 located above a lower head 2 which is connected with a receptacle, 3 such as a barrel or the like, from which the liquid is to be pumped. The pump also includes an upper head 4, cylinder 1 being clamped between the upper and lower heads by the usual rods which are shown but not numbered. The pump is hand operated by a crank 5 for the purpose of reciprocating the pump piston (not shown), oil being dispensed upwardly through an extension 6 to

a head at the end thereof and thence through a short connecting nipple 7 to the nozzle 8.

The nozzle which is screwed on to the end of the nipple includes the horizontally located hollow body 8 having a closed outer end portion 9 from which a short sleeve 10 extends vertically, and is exteriorly threaded to receive a closing cap 11. Between the cap and the upper end of the sleeve 10 a leather washer 12 is positioned and is clamped between the under side of the cap and a metal ring 13 which lies against the upper end of the sleeve 10. The ring 13 has a relatively large central opening. The leather washer 12 also has a central opening of smaller diameter than the opening through the ring 13.

Below the sleeve 10 and at the lower part of the closed end portion 9 of the nozzle is a vertical outlet section, the inner walls of which are formed to make a short vertical cylindrical opening 15 which communicates with a larger opening in the upper part of the outlet member 14. A valve member comprising rod 16 is mounted vertically to extend through the outlet member 14 having a diameter such that it is adapted to closely fit the cylindrical opening at 15, but not so close that it will bind thereagainst. The rod 16 adjacent its upper portion is provided with radially extending guide vanes 17 and at its upper end with a large head or valve 18 which lies above the outlet member 14 and in its lower position bears against the horizontal ledge or valve seat 19 surrounding the opening which extends downwardly through the outlet member 14.

In alignment with the rod 16 and located above the same, is a second rod 20, somewhat larger in diameter, which passes upwardly through the cap 11 and through the opening in the leather washer 12, the downward extensions 12^a thereof pressing against the sides of the rod 20. The lower end of the rod is somewhat reduced in size and equipped with a ball 21 which seats in a suitable socket formed in the head 18 and is retained therein by an annular lip 22 which passes over the upper portion of the ball 21 so as to connect the two rods 16 and 20 but permit a universal movement of one with respect to the other by reason of the ball and socket joint described.

At the inner end and under side of the nozzle 8 a lug 23 is integrally cast extending downwardly therefrom, to which a trip bar 24 is pivotally connected by means of the pivot pin 25, the inner end of the bar 24 being di-

vided so as to pass at each side of the lug 23. The bar 24 extends to substantially underneath the outlet member 14 and at its outer end is provided with oppositely extending curved arms 26 between which is a recess 27 of the form best shown in Fig. 4. Between the ends of the bar 24 and at its under side it is further provided with an integral downwardly extending lug 28.

- 10 In the upper end portion of the rod 20 above the cap 11 an opening is made through which a U-shaped rod freely passes. This U-shaped rod has downwardly extending legs 30, one at each side of the nozzle, each 15 of which is threaded at its lower end to adjustably connect with the upper end of a connecting member 31. Each of the members 31 is reduced in size at its lower end portion, as indicated at 32, and each of the parts 20 32 at its lower end is equipped with a ball 32^a to have a ball and socket connection with the sockets 33, one of which is connected with and located at the upper side and outer end of each of the arms 26.
- 25 On operating the crank 5, oil or other liquid will be forced into the nozzle 8 entirely filling the space within the same and the pressure exerted thereby forces the part 12^a of the leather washer 12 snugly against 30 the rod 20 and also forces the head 18 downwardly against the ledge 19. Oil cannot escape in such case by reason of pressure caused by attempted pump operation, as increase in pressure merely makes the head 18 fit the 35 more snugly against the seat 19. The force against the head 18 is not excessive, however, and the trip bar 24 may be readily elevated so as to permit the escape of oil through the outlet member 14. On elevation of the bar 24 40 the U-shaped member 29 connected to the rod 20 lifts said rod and also the valve rod 16 so that the head 18 is lifted above the seat 19 and the lower end of the rod 16 is lifted above the short cylindrical opening at 15. One way 45 of lifting the bar 24 is to place a liquid receptacle, such as indicated at 34 in Fig. 1, underneath the bar and push upwardly thereon, inward movement of the receptacle being limited by the downwardly projecting lug 28. The receptacle will catch the liquid and when it is moved downwardly away from the bar 24, the valve rod 16 will likewise move downwardly, fit into and fill the outlet opening at 15, forcing all of the oil ahead of 50 it and positively stopping any drip of oil from the nozzle. Another way of operating the bar 24 is by hand; this is used for instance, in filling bottles. A bottle is placed underneath the outlet member 14, the neck thereof 55 passing upwardly in the recess at 27 and the bar 24 is lifted by hand using the same hand which holds the bottle. When the bottle is filled it, with the hand holding it, is moved downwardly whereupon the flow of liquid 60 from the nozzle is immediately and automat-

ically cut off with a total elimination of any drip which otherwise would occur.

In Figures 5 to 8 inclusive some modifications are shown, particularly with respect to the nozzle outlet and the means used for insuring that no drip of oil shall escape from the outlet. In Fig. 5, the rods 20 and 16 shown in Fig. 3 are made integral, the upper section 200 being somewhat larger in cross section than the lower section 160. The head 75 18 is dispensed with but substantially at the junction of the two sections 160 and 200, an enlargement 35 is made serving as an abutment against which the lower end of a light coiled spring 36 bears, the upper end 80 engaging against the down turned portions 12^a of the leather packing 12. The lower end of section 160 is provided with a collar 161 somewhat larger in diameter below which is a short downward extension 162 which, in its 85 lower position, fills the outlet opening at 15 and extends entirely through the same, while the collar 161 seats against a ledge in the outlet section 14 around the wall or opening at 15. This completely closes the nozzle against 90 any passage of oil. The lifting of the connected sections 200 and 160 is effected by the same means shown in Figs. 1, 2, 3 and 4.

In all of the nozzle constructions a vertical baffle 8^a is located within and adjacent the 95 outer portion of the nozzle 8 so that the oil must pass over the same and is not directed laterally against any of the heads such as 22 shown in Fig. 3 seated on the seat 19 or the other oil stopping devices used in Figs. 6, 7 100 and 8 which will now be described.

In Fig. 6, the rod shown in Fig. 3, is replaced by a somewhat similar rod 201 which at its lower end is equipped with a narrow collar 37 above which is a nut 38 screwing on 105 to an enlarged portion of the rod 201, there being clamped between the collar 37 and the nut 38, a valve 39 of suitable yielding material, such as leather, with a metal washer 40 above the valve. The rod 16 is the same as 110 that shown in the construction illustrated in Fig. 3 and it is permanently attached in any suitable manner to the lower end of the rod 201. This to all intents and purposes is the same in effect as the structure shown in Fig. 115 3, the head 18 being replaced by a yielding valve 39 so that a better seat may be made against the seat 19.

In Figs. 7 and 8 a still further form of construction is shown wherein the combination 120 of the two drip stopping devices shown in Figs. 5 and 6 is effected. The rod 201 with its collar 37, nut 38, leather valve 39 and washer 40 are substantially the same as that shown in Fig. 6 except the lower end of the rod 201 has a recess or opening which is bored upwardly from the lower end of the rod and in which a light coiled spring 41 is located. The rod 163 in the lower part of the vertical extension 125 to the nozzle has its upper end slidably re- 130

ceived in the rod 201 and a pin 42 passes through the upper end of rod 163 which at its ends, is received in vertical slots 43 in the lower end of rod 201. Rod 163 is reduced in 5 diameter at its lower end and has an extension 164 which in lower position passes through and substantially fills the opening at 15; while the shoulder between the rod 163 and its extension 164 seats against an angular 10 flange around the opening at 15.

This provides three stoppages against the passage of oil from the nozzle when the rod 163 is in its lower position. The first is effected by the valve 39 seated on the seat 19; 15 the second by the shoulder at the lower end of the rod 163 seating on the angular ledge around the opening 15; and the third by the extension 164 practically completely filling and extending entirely through the opening 20 at 15. The spring 41 insures that the rod 163 will be held in lower closing position when the upper rod 201 is in lower position and permits a certain latitude in manufacture that would not be present if the rod 163 was 25 permanently secured to or integral with the rod 201.

In practice it is desirable that the bar 24 be limited in its upward movement and for this purpose it is equipped at its upper side 30 with a lug 24^a, shown in Fig. 3, and located directly under a boss 8^b at the under side of the nozzle 8. Accordingly, when the bar 24 is lifted, its upward movement is stopped when the lug 24^a strikes across the boss 8^b as 35 is evident.

This construction of liquid dispensing nozzle is simple, practical and effective. It has been tested and tried and has proved very satisfactory, positively stopping drip and 40 eliminating this defect which heretofore has been suffered. No means is required and none is used to catch and return the drip as the drip is eliminated. The invention is defined in the appended claims and is to be considered 45 comprehensive of all forms of structure coming within their scope.

I claim:

1. In a device of the class described, a horizontally located hollow nozzle, an outlet 50 member depending from the outer end of said nozzle having a vertical opening therethrough restricted at its lower end for a short distance and enlarged above said restricted portion, a rod passing vertically through the 55 outlet member, an enlarged head at the upper end of the rod adapted in lower position to close the upper end of the opening in the outlet member and extend beyond the edges of the same, said rod in lower position filling 60 the restricted portion of the opening and ex-

tending therethrough, a trip bar pivotally mounted at its inner end on and below said nozzle and extending forward to substantially below the lower end of the outlet member, a second rod extending upwardly 65 through the nozzle, and connected at its lower end with said head, a U-shaped member connected at its middle to the upper end portion of the second rod and having depending sides 70 passing one at each side of the front portion of the nozzle, and means connecting said depending sides with the trip bar.

2. In a construction containing the elements in combination defined in claim 1, the front end of said trip bar being recessed rearwardly whereby a recess is provided in the bar directly below the lower end of the outlet member, and a lug connected with the under side of said trip bar a distance back of said 75 recess.

3. In a construction containing the elements in combination defined in claim 1, said head on the first rod being formed with a socket and said second rod at its lower end with a ball received in said socket and said 80 rod at its upper end portion having an opening therethrough through which the U-shaped member loosely passes, and means providing a pivotal joint connection between the trip bar and the lower end of each of the 85 sides of said U-shaped member.

4. A device of the class described comprising, a nozzle having an outlet passage and an outlet opening at the outer end of said passage, a valve seat at the inner end of said passage, a valve member extending through said passage, a poppet type valve on the inner end of said valve member engageable with said seat, the outer end of said valve member being associated with said outlet opening to 90 serve as a piston type valve whereby longitudinal movement of the valve member will open or close both valves and means for moving the valve member longitudinally.

5. A device of the class described comprising, a nozzle having an outlet passage and a restricted outlet opening in the outer end thereof, a valve seat at the inner end of said passage, a valve member extending through said passage, the outer end thereof adapted 100 to extend into said restricted outlet opening and being associated therewith to form a piston type valve, a poppet type valve at the inner end of said valve member engageable with said seat whereby longitudinal movement of the valve member will open or close both valves and means for moving the valve member longitudinally.

In testimony whereof I affix my signature.

THOMAS B. BENNETT.
